UNITED STATES PATENT OFFICE.

JAMES ALBRITTON, OF ROCKPORT, TEXAS.

WAGON-BRACE.

1,322,992.

Specification of Letters Patent. Patented Nov. 25, 1919.

Application filed October 13, 1916. Serial No. 125,401.

To all whom it may concern:

Be it known that I, JAMES ALBRITTON, a citizen of the United States, residing at Rockport, in the county of Aransas and 5 State of Texas, have invented certain new and useful Improvements in Wagon-Braces; and I do hereby declare the following to be a full, clear, and exact description of the invention, such as will enable others skilled 10 in the art to which it appertains to make and use the same.

This invention relates to a wagon brace and more particularly to means for bracing the thimbles upon an axle of the wagon and 15 has for its primary object the provision of means for obviating the danger of thimbles breaking under excessive strain and weight.

Another object of this invention is to provide truss rods carried by the bolster of an 20 axle and secured to the thimbles, whereby the thimbles will be braced and prevented from breaking downwardly under excessive strain or weight.

A further object of this invention is the 25 provision of means upon the thimbles for fastening the ends of the truss rods thereto, whereby they may be readily removed and renewed when desired.

A still further object of this invention is 30 the provision of a wagon brace of the above stated character which shall be simple, durable and efficient, and which may be manufactured and sold at a comparatively low cost.

35 With these and other objects in view as will become more apparent as the description proceeds, the invention consists in certain novel features of construction, combination and arrangement of parts as will be 40 hereinafter more fully described and claimed.

For a complete understanding of my invention, reference is to be had to the following description and accompanying drawing, in which—

Figure 1 is a front elevation partly in section of a wagon brace, constructed in accordance with my invention,

Fig. 2 is a fragmentary top plan view of 50 the same,

Fig. 3 is a detail sectional view taken on the line 3—3 of Fig. 1 illustrating the means of supporting the truss rods on the bolster,

Fig. 4 is a detail view of a modified form 55 of means of securing the truss rods to the thimbles, and

Fig. 5 is a fragmentary vertical sectional view of the same.

Referring in detail to the drawing, the numeral 1 indicates an axle of a wagon having mounted thereon in the usual manner a bolster 2, which may be of any desired construction.

Mounted upon each end of the axle 1 are thimbles 3 having formed upon their inner 65 ends flanges 4 which are provided with a plurality of apertures for receiving truss rods which will be hereinafter more fully described.

Substantially U-shaped clamps 5 are secured to the bolster 2 as clearly illustrated in Fig. 1 and have their arm or leg portions bent to form hooks 6 for receiving truss rods 7 upon each side of the bolster 2. The truss rods 7 have each end bent downwardly in 75 an inclined plane, and screw threaded. The screw threaded ends being inserted through apertures in the upper ends of the flanges 4 and receiving nuts 8 thereon to support and brace the thimbles 3 to prevent them from 80 breaking downwardly under excessive strain or weight.

A truss rod 9 has each end screw threaded and extends parallel with the axle 1 and upon the under face thereof and has its ends 85 inserted through the flanges 4 of the thimbles 3 and receives nuts 10 upon the ends thereof for securing the truss rod to the thimbles 3 to prevent them from buckling or bending upwardly under excessive strain or weight. 90

Referring to my modified form of invention or means for securing the truss rods to the thimbles it consists of a clamping consisting of a pair of sections 11 and 12. This form of clamp is especially adapted for use 95 in connection with ordinary thimbles now used upon wagons and clearly illustrated in Fig. 5, having the usual shoulders 13 which the wheels engage and the collars 14 located at their innermost ends. The sections 11 100 and 12 are placed between the collars 14 and shoulders 13 as clearly illustrated in Fig. 5, and secured thereon by means of bolts 15. The section 11 of the clamp is provided with a pair of apertures 16 for the reception of 105 the ends of the truss rods 9, while the section 12 is provided with an aperture 17 for receiving the end of the truss rod 9.

From the foregoing description taken in connection with the accompanying drawing, 110 it will be readily noted that the form of clamps provide means whereby the truss

rods may be readily attached to thimbles of ordinary construction without the added expense of making specially constructed thimbles to attach the truss rods thereto.

5 While I have shown and described the preferred embodiment of my invention, it will be understood that minor changes in construction, combination and arrangement of parts may be made without departing 10 from the spirit and scope of the invention as claimed.

Having thus described my invention, what I claim is:

15 A wagon brace including an axle having a thimble on each end and a bolster mounted on said axle, flanges formed on the inner

ends of the thimbles, supporting brackets secured to the bolster adjacent each end thereof, a pair of rods supported by said brackets on each side of the bolster and having their 20 ends secured to the flanges above the horizontal axis of the axle, and a rod extending parallel with the axle and disposed under its lower face and secured to the flanges below the horizontal axis of the axle. 25

In testimony whereof I affix my signature in presence of two witnesses.

JAMES ALBRITTON.
